UNITED STATES PATENT OFFICE.

SWAN R. STROM, OF CHICAGO, ILLINOIS, ASSIGNOR TO PRESSED STEEL CAR COMPANY, OF PITTSBURGH, PENNSYLVANIA, A CORPORATION OF NEW JERSEY.

WASHER AND SHAFT.

1,381,360.

Specification of Letters Patent. Patented June 14, 1921.

Application filed February 24, 1919. Serial No. 278,972.

To all whom it may concern:

Be it known that I, SWAN R. STROM, a citizen of the United States, residing in Chicago, in the county of Cook and State of Illinois, have invented certain new and useful Improvements in Washers and Shafts, of which the following is a specification.

An object of the present invention is to provide a washer which is capable of longitudinal adjustment on a shaft and which is adapted to be held in preferred adjusted position on the shaft by means of a pin or other suitable means which passes through a single hole in the shaft and through one pair of a plurality of pairs of holes in the washer which are spaced apart in a direction longitudinally of the shaft and also spaced at an angle to each other, thus providing a plurality of adjustments without making a plurality of holes in the shaft and consequent weakening of the same.

A more specific object of the invention is to provide a device for adjusting discharge door operating mechanisms to cars when the dimensions of such cars vary in a direction longitudinally of the mechanisms or in a direction longitudinally of the shafts for operating such mechanisms, or when component parts of the mechanism on the shaft and discharge doors do not register.

Another object of the invention is to provide a discharge door operating shaft with means which will permit of the moving of the power applying device on the shaft a sufficient distance to compensate for variations in the length of the car body to which the shaft is applied and will hold such power applying device in preferred adjusted position.

A further object of the invention is to provide a discharge door operating mechanism with means which will permit of the moving of the discharge door operating shaft a sufficient distance to compensate for variations in the length of the car body to which the shaft is applied and to move the door supporting rollers into their proper positions relative to the shoes which are secured to the doors.

Referring now to the drawings in which like reference characters refer to like parts, Figure 1 is an end view of a portion of a car and discharge door operating mechanism embodying the invention; Fig. 2 is a sectional view of the same taken on the line

2—2 of Fig. 1 a portion of the length of the car being broken away, the discharge door operating mechanism being shown in its preferred position; Fig. 3 is a similar sectional view showing the mechanism in an adjusted position; Fig. 4 is a side view of one of the washers; Fig. 5 is a face view of the same; Fig. 6 is a side view of another washer; and Fig. 7 is a face view of the same.

Referring now in detail to the drawings, 1 indicates the car body which may be of any desired type or construction, the car body illustrated in the drawings being of what is known as the general service type, and is provided with side walls 2, end walls 3, transverse underframe members 4 and discharge doors 5, all of which parts are of the usual form and construction.

The discharge doors 5 may be operated by the use of any suitable mechanism, but for illustrative purposes a mechanism has been shown in the drawings which is fully described in United States Patent #791348 granted to Charles A. Lindstrom and John F. Streib May 30, 1905. This mechanism comprises a shaft 7 which preferably extends in a direction longitudinally of the car and is operatively mounted in suitable bearing members 8 which are secured to the transverse underframe members 4. Between these transverse members 4 the shaft is provided with rollers 9 that are adapted to engage with shoes 10 which are secured to the doors 5. Each of these rollers is preferably provided with a spirally grooved drum 11 upon which a chain 12 is adapted to be wound, one end of such chain being secured to the drum and the opposite end being secured to the shoe member or to the door. The outer end portion of this shaft preferably extends beyond the end wall 3 and is provided with a ratchet wheel 13 and hand lever 14 or any other suitable means for rotating the shaft. In the mechanism illustrated, the shaft, adjacent its outer end portion, is journaled in a bearing member 15 which in turn is mounted in a member 16 which is preferably secured to the end wall 3. The ratchet wheel 13, hand lever 14 and bearing member 15 are held in their proper operative positions on the shaft relative to each other and to the end wall 3 by washers 17 and 18, the washer 17 engaging with the bearing members 15 and 16 and the washer 18 engaging with the hand lever 14. These washers 17

100

110

and 18 are substantially alike, each having a sleeve portion 19 and a flange portion 20. The sleeve portion 19 of the washer 17 is provided with pairs of holes 21, 22 and 23 which are each adapted to register with a hole 24 in the shaft, such pairs of holes being spaced apart longitudinally of the shaft and at an angle of substantially 60° from each other. The washer 18 is also provided with pairs of holes 25, 26 and 27 which are spaced in the same manner as the holes in the washer 17 and are adapted to register with a hole 28 in the shaft.

In building a plurality of cars of the same type it has been found that the rollers 9 will not in all cases register with the shoes 10, due to unavoidable inaccuracy in commercial production and heretofore it has, in many cases, been difficult to apply the discharge door operating mechanism to different cars of the same type without drilling extra holes in the shaft 7 to enable the washers to be secured to the shaft in such a manner as to compensate for such inaccuracies after the mechanism has been mounted on the car. By the use of the washers 17 and 18 these extra holes in the shaft are rendered unnecessary, and it will be noted that when the door operating mechanism is applied to a car in which the shoes on the door are in their proper positions relative to each other and to component parts of the car as shown in full lines in Fig. 1 of the drawings, a pin or other suitable means is passed through the pair of holes 22 in the washer 17 and through the hole 24 in the shaft and a pin is passed through the pair of holes 26 in the washer 18 and through the hole 28 in the shaft thus holding the door operating shaft, rollers and power applying device against longitudinal movement. When the rollers on the shaft do not register with the shoes on the doors as shown in dot and dash lines in Fig. 1 of the drawings the shaft together with the rollers may be moved backward or forward until the shoes and rollers do register as shown in full lines in Fig. 1 and if it is necessary to move the shaft and rollers forward as shown in full lines in Fig. 2 to obtain such registration, a pin is passed through the pair of holes 27 in the washer 18 and through the holes 28 in the shaft 7 and a pin is passed through the pair of holes 21 in the washer 17 and through the hole 24 in the shaft 7, but if on the other hand it is necessary to move the shaft and rollers backward as shown in dot and dash lines in Fig. 2 to obtain such registration, a pin is passed through the pair of holes 25 in the washer 18 and through the hole 28 in the shaft and a pin is passed through the pair of holes 23 in the washer 17 and through the hole 24 in the shaft 7. It will here be noted that in this

adjustment to different cars, the shaft and rollers only are moved, but it is to be understood that the power applying device may be moved on the shaft to adjust the mechanism to cars of the same type which vary in length due to unavoidable inaccuracies in commercial production. When the door operating mechanism is applied to a car which is of the proper length, a pin, or other suitable means is passed through the pair of holes 22 in the washer 17 and through the hole 24 in the shaft and a pin is passed through the pair of holes 26 in the washer 18 and through the hole 28 in the shaft, thus holding the shaft and the power applying device against longitudinal movement. When the discharge door mechanism is to be applied to a car the length of which is shorter than that intended, a pin is passed through the pair of holes 21 in the washer 17 and through the hole 24 in the shaft and a pin is passed through the pair of holes 27 in the washer 18 and through the hole 28 in the shaft. When the discharge door mechanism is to be applied to a car the length of which is greater than that intended, a pin is passed through the pair of holes 23 in the washer 17 and through the hole 24 in the shaft and a pin is passed through the pair of holes 25 in the washer 18 and through the hole 28 in the shaft.

The washers have been described in connection with what is known as the "creeping shaft" discharge door operating mechanism but it will be understood that these washers may be applied to a shaft to be used for any other purpose.

Having thus described the invention what I claim as new and desire to secure by Letters Patent is:

1. In a discharge door operating mechanism, an operating shaft having openings formed therein, a power applying device on said shaft, washers on said shaft adapted to hold said power applying device in its proper operative position, each of said washers having a plurality of transverse openings therein spaced apart longitudinally and each adapted to register with one of the openings in said shaft for longitudinal adjustment of said mechanism, and means adapted to pass through one of the openings in said washer and one of the openings in said shaft to hold said washer in adjusted position.

2. In a dump car, the combination with a discharge door operating mechanism, of an operating shaft forming part of said mechanism, said shaft having openings formed therein, a power applying device on said shaft, and washers on said shaft adapted to hold said power applying device and shaft in their operative positions relative to each other, said washers having a plurality of transverse openings formed therein, said

- openings being spaced apart longitudinally of the washer and adapted to register with one of the openings in said shaft for longitudinal adjustment of said mechanism to 5 said car.
3. In a dump car, the combination with the discharge door operation mechanism, of an operating shaft forming part of said mechanism said shaft having openings 10 formed therein, a power applying device on said shaft, and washers on said shaft adapted to coöperate with said power applying device for adjusting said mechanism to said car, said washers each having a plurality of 15 transverse openings formed therein spaced apart longitudinally and each adapted to register with one of the openings in said shaft for adjustment of said mechanism to said car.
4. In a dump car comprising an end wall and transverse underframe members, drop doors arranged between said members and means mounted on said car for opening and closing said doors, said means comprising a 20 shaft having an opening formed therein and a power applying device on said shaft, a washer on said shaft for holding said power applying device and shaft in proper operative positions relative to each other, said 25 washer having a plurality of transverse openings therein spaced apart longitudinally, and each adapted to register with one of the openings in said shaft for longitudinal adjustment of said mechanism to said 30 car.
5. In a dump car, the combination with the discharge door operating mechanism, of a shaft forming part of said mechanism, said shaft being journaled in a bearing member 35 at the end of the car, said bearing member being mounted in another bearing member secured in said car, a power applying device on said shaft, a washer on said shaft adapted to engage said power applying device, and a washer on said shaft adapted to 40 engage said bearing members, said washers each having a plurality of transverse openings therein spaced apart longitudinally, and each adapted to register with one of the 45 openings formed in said shaft for longitudinal adjustment of said shaft relative to said power applying device and to said car, and means passed through the opening in said washer and shaft for securing said washers to said shaft.
6. In a dump car, the combination with a discharge door operating mechanism, of a shaft forming part of said mechanism, said shaft having openings formed therein, a washer mounted on said shaft adapted to engage portions of said 50 car, said washer having a plurality of transverse openings formed therein spaced apart longitudinally, and each adapted to register with the opening in said shaft for longitudinal adjustment of said washer and shaft 55 relative to each other.
- In testimony whereof I affix my signature in the presence of two witnesses.
